UNITED STATES PATENT OFFICE.

ERNEST ZEIDLER, OF MARSHFIELD, WISCONSIN.

CHEESE-BOX.

1,388,396.

Specification of Letters Patent. Patented Aug. 23, 1921.

Application filed February 7, 1921. Serial No. 443,028.

To all whom it may concern:

Be it known that I, ERNEST ZEIDLER, a citizen of the United States, residing at Marshfield, in the county of Wood and State of Wisconsin, have invented certain new and useful Improvements in Cheese-Boxes, of which the following is a specification, reference being had therein to the accompanying drawing.

10 The invention relates to cylindrically shaped cheese boxes, however, it is applicable to various types of boxes and has for its object to provide a metallic band angular shaped in cross section, which metallic band 15 is disposed on the edge of the cover or body of the box in such a manner that one of its flanges may be secured to the cover or bottom of the box in a channel of which cover or bottom the flange of the cover or the wall 20 of the body of the box is disposed and held by the other flange of the band, said flange being provided with an annular bead which registers with the edge of the cover or the edge of the bottom of the body of the box, 25 but arches the same in such a manner that the flange of the band secured to the flange of the cover or the wall of the body of the box will exert an inward pressure on said flange or wall for holding said flange or 30 wall of the cover or bottom of the box. It has been found that by so reinforcing and securing together parts of the box that said flange or wall of the box will be securely held in the groove of the cover or bottom 35 of the box in such a manner that a tight joint is formed and if the wall or flange expands incident to dampness or contracts incident to dryness, the joint will be maintained in a tight condition. It has also 40 been found that where the bands are split and placed in position and the ends thereof drawn together, that the flange of the cover or wall of the box will be forced tightly into the groove of the cover or the bottom of the 45 body of the box thereby insuring a tight joint.

A further object is to provide a head for a cylindrical box comprising a disk of wood and a disk of fibrous material commonly called wall board, said disk of fibrous material being of smaller diameter than the disk of wood and adapted to be concentrically

disposed thereon, thereby forming an annular groove adjacent the periphery of the wood disk for the reception of the marginal edge of the flange of the cover or the body of the box, said disk being secured together by means of securing means passing through the flange of a band and through said disk, said band being also provided with a flange 60 engaging the periphery of the cover flange or the wall of the body of the box and secured thereto and so shaped as to engage said wall and hold the same in the annular groove.

With the above and other objects in view the invention resides in the combination and arrangement of parts as hereinafter set forth, shown in the drawings, described and claimed, it being understood that changes 70 in the precise embodiment of the invention may be made within the scope of what is claimed without departing from the spirit of the invention.

In the drawings:

Figure 1 is a side elevation of the box.

Fig. 2 is a horizontal sectional view taken on line 2—2 of Fig. 1.

Fig. 3 is a detail perspective view taken on line 3—3 of Fig. 2.

Fig. 4 is a detail vertical sectional view through one side of the cover and a portion of the body of the box.

Fig. 5 is a detail sectional view in perspective of one side of the body of the box, 85 showing the bottom thereof formed from a single piece of material.

Fig. 6 is a detail perspective view of a portion of one of the metallic bands.

Referring to the drawings, the numeral 1 designates the body of the box and 2 the cover therefor. The box is a cylindrical one and the body 1 thereof comprises a cylindrical portion 3 formed from fibrous material and the bottom 4. Bottom 4 is formed 95 from disks 5 and 6, the disk 5 being preferably made of wood, and the disk 6 of fibrous material, commonly known as wall-board. Disk 6 is smaller than the disk 5 and is concentrically disposed thereon, thereby forming an annular channel 7 which receives the lower end of the wall 3, and in which channel said wall is held by an annular band 8. The annular band 8 is sub-

stantially right angular shaped in vertical cross section and has its flange 9 in engagement with the under face of the disk 5 and its flange 10 in engagement with the periphery of the wall 3. The flange 9 is secured to the bottom 4 by means of staples 11 which pass through said flange and through the disks 5 and 6, thereby not only securing the band 8 in place, but also securing the disks 10 5 and 6 together so that they will reinforce each other. Passing through the flange 10 are staples 12, which also pass through the wall 3, thereby securely holding said wall at its lower end in the channel 7. It has been 15 found however, that incident to dampness the wall will expand and when dried will contract, and when so contracted, looseness develops in the joint; therefore to obviate this difficulty, the flange 10 is provided 20 adjacent its lower end with an annular bead 13, which arches the periphery 14 of the bottom 4 in such a manner that the flange 10 does not engage with the same. By this 25 construction it will be seen that after the band has been placed in position and its ends 15 and 16 drawn together, that said flange 10 will force the lower end of the wall 3 into binding engagement with the wall 17 of the channel 7 after which the ends are preferably 30 spot welded as at 18 for securely holding them together and then the flanges 9 and 10 are stapled at 11 and 12. It will be seen that there is a binding engagement and a contracting force on the lower end of the 35 wall 3 at all times either when the wall expands or contracts.

By referring to Fig. 4 in which a sectional view is shown through one side of the cover 2, the construction is the same with the exception that the flange 10 of the metallic band 8 is secured to the flange 19 of the cover, said flange 19 being preferably formed from fibrous material or wall board, and the numerals applied to said figures are 45 the same.

Referring to Fig. 5 wherein a modified form of bottom is shown, it will be seen that the bottom is formed from a single piece of material, preferably wood, and that the 50 other construction is the same as that shown in Fig. 3.

From the above it will be seen that securing means is provided for a cylindrical box wherein an angularly shaped band in cross 55 section is utilized in such a manner that one of its flanges may be secured to the bottom of the box and its other flange secured to the side of the box and provided with means whereby a constant pressure will be applied 60 to the side of the box for maintaining the edge thereof in an annular groove in the bottom of the box.

The flange 9 of the band is crimped as 65 shown at 20, which crimping not only forms the band into a ring, but also allows the

band to be easily contracted and uniformly contracted when the ends 15 and 16 are drawn together for spot welding at 18. The crimping also allows the flange 10 to conform to the periphery of the wall 3, so that a uniform pressure will be applied on the entire wall.

The invention having been set forth what is claimed as new and useful is:—

1. The combination with a cylindrical wall 75 of a receptacle disposed in an annular groove adjacent the periphery of the head of the receptacle, of means for securing said head and wall together and holding the wall in the groove in engagement with the bottom 80 of the groove, said means comprising an annular band having substantially right angularly disposed flanges, one of said flanges being secured to the head, the other flange being secured to the wall, and an annular 85 struckout bead carried by the wall secured flange and having its inner face spaced from the edge of the head.

2. The combination with a receptacle having a wall disposed in a groove of a receptacle head, of means for securing said head and wall together and holding the wall in close engagement with the bottom of the groove, said means comprising a metallic strip substantially right angled in cross section and having two flanges, one of said flanges being secured to the receptacle head and the other flange secured to the wall, and a bead carried by the wall secured flange and having its inner side spaced from the edge 100 of the head.

3. The combination with a receptacle having a wall disposed in an annular groove of a receptacle head, said head being cylindrically shaped, said groove of the head being 105 formed by superimposed disks of different diameters, an annular band having substantially right angularly disposed flanges, one of said flanges being secured to the receptacle head and the other flange to the cylindrical wall, and an annular bead carried by the wall secured flange, said bead having its inner side spaced from the edge of the lower disk forming the head.

4. A cylindrical box body comprising a 115 cylindrical wall and a disk shaped bottom, said bottom being formed by superimposed disks, one of said disks being smaller than the other thereby forming an annular groove for the reception of the cylindrical wall, an 120 annular band for securing said bottom and wall together, said band being provided with right angularly disposed flanges, one of said flanges being secured to the bottom, the other flange being secured to the wall, and an annular 125 bead carried by the wall secured flange and having its inner side spaced from the periphery of the bottom.

5. The combination with the body of a box comprising a cylindrical wall disposed 130

in an annular groove of a disk, of means for securing said wall and disk together and holding the wall in the annular groove, said means comprising a band right angular in cross section and having one of its flanges secured to the disk and one of its flanges secured to the wall, and a bead carried by

the wall secured flange, said bead having its inner side spaced from the periphery of the disk.

10 In testimony whereof I hereunto affix my signature.

ERNEST ZEIDLER.
